UNITED STATES PATENT OFFICE.

ALBERT B. MASON, OF FULTON, NEW YORK.

EXCELSIOR PAD.

Application filed July 27, 1922. Serial No. 577,880.

To all whom it may concern:

Be it known that I, ALBERT B. MASON, citizen of the United States, residing at Fulton, in the county of Oswego and State

5 of New York, have invented certain new and useful Improvements in Excelsior Pads, of which the following is a specification.

This invention relates to what are known to trade as excelsior pads, cushions or mats 10 and has for its object the production of those pads in a manner such that the excelsior will be evenly distributed and that it will be held in place in the tubular sheath or jacket even when such jacket be made of 15 unusual width.

The invention therefore consists in the formation and construction of excelsior pads and the like substantially as herein set forth.

In the accompanying drawings which 20 form a part of this specification Fig. 1 represents an excelsior pad in perspective; Fig. 2 is a longitudinal transverse section showing the general widthwise arrangement of the fibers within the tube; and Fig. 3 indicates one way of attaching the fibers to the sheath or tube.

The excelsior pads heretofore made have been comparatively narrow and have not therefore required any particular attention 30 to the arrangement of the fibers to insure even distribution widthwise as well as in thickness. Nor has it been necessary to secure the excelsior from displacement in the tubes or from sliding out of them in handling the pads.

However with the advent of wide tubes or pads the necessity for such distribution and securing has arisen. Take for example a tube 18 to 20 inches wide and 1 to 2 inches 40 thick cut square or into pads 3 to 4 feet long the old manner of distributing the fiber mainly lengthwise of the tubes is entirely inadequate and in handling the pads the excelsior becomes bunched laterally or spills 45 from the tube.

These difficulties have been overcome by distributing the fibers more or less widthwise of the tube and securing them in some adequate way therein.

In Fig. 2 the fibers 4 are illustrated in 50 widthwise arrangement within the tube 5 and in Fig. 3 are indicated at 6 and 7 streaks of adhesive—glue or paste—applied to the inner surface of the tube whereby the excelsior is stuck in place during the process of 55 manufacturing the pad.

The streaks of adhesive substance are here shown on the lower wall of the flat tube but they may be applied to any part of the inner surface of the tube in any direction and 60 in any number.

The invention claimed is:—

1. An excelsior pad consisting of a flattened tube of paper with a filling of excelsior 65 in which the strands or fibers are intermingled and extend in a general transverse direction as to the tube and throughout the length thereof.

2. An excelsior pad consisting of a flattened paper tube having a filling of excelsior 70 the strands or fibers of which extend in a general transverse direction as to the tube and an adhesive on the inner wall of the tube to hold the excelsior from displacement.

3. The method of making excelsior pads, 75 consisting in applying strips of an adhesive substance to a web of paper and throughout the length thereof, depositing a layer of excelsior upon the paper with the strands of fibers thereof extending in a general transverse direction with respect to the web, folding the sides of the web over the excelsior and uniting their edges thereby forming a flat tube and bringing the excelsior into contact with the adhesive for the purpose set 80 forth.

ALBERT B. MASON.
